(57) **CLAIM**

The ornamental design for a portable mobility scooter, as shown and described.

DESCRIPTION

FIG. 1 is a front, right, top perspective view of a portable mobility scooter showing our new design;

FIG. 2 is a back, left, bottom perspective view thereof;

FIG. 3 is a folding state of the portable mobility scooter after the seat is removed as shown in FIG. 1;

FIG. 4 is a front view thereof;

FIG. 5 is a back view thereof;

FIG. 6 is an enlarged left view thereof;

FIG. 7 is an enlarged right view thereof;

FIG. 8 is a top view thereof;

FIG. 9 is a bottom view thereof;

FIG. 10 is an enlarged view of the encircled area 10 of FIG. 1;

FIG. 11 is an enlarged view of the encircled area 11 of FIG. 1;

FIG. 12 is an enlarged view of the encircled area 12 of FIG. 1;

FIG. 13 is an enlarged view of the encircled area 13 of FIG. 1;

FIG. 14 is an enlarged view of the encircled area 14 of FIG. 2; and,

FIG. 15 is an enlarged view of the encircled area 15 of FIG. 2.

The broken lines shown in the figures depict portions of the portable mobility scooter that do not form part of the claimed design.
